FIG. 31 is a right side elevational view thereof; FIG. 32 is a left side elevational view thereof; FIG. 33 is a top plan view thereof; FIG. 34 is a bottom plan view thereof; and, FIG. 35 is another perspective view thereof. The broken lines in each of FIGS. 1-5, 7-20, 22-32, and 34-35 show portions of the electronic device that form no part of the claimed design. The broken lines in each of FIGS. 9 and 11 show portions of the electronic device that form no part of the claimed design, and also show a card reader that is environmental structure and forms no part of the claimed design. The broken lines in FIG. 10 show portions of the electronic device that form no part of the claimed design, and also show a card reader and a card that are environmental structure and form no part of the claimed design. The surface shadings and contour lines shown in FIGS. 1-35 represent the three-dimensional character and contour of the electronic device, and are not intended to limit the electronic device to any particular materials, colors, or surface decorations. The different surface shadings are used to indicate contrasting materials. The electronic device includes a base portion, an arm portion pivotably coupled to the base portion, and a display portion pivotably coupled to the arm portion. In the first configuration of the electronic device illustrated in FIGS. 1-11, the arm portion is pivoted to an upper position relative to the base portion and the display portion is pivoted to a front facing position relative to the arm portion. In the second configuration of the electronic device illustrated in FIGS. 12-19, the arm portion is pivoted to the upper position relative to the base portion and the display portion is pivoted to a rear facing position relative to the arm portion. In the third configuration of the electronic device illustrated in FIGS. 20-27, the arm portion is pivoted to a lower position relative to the base portion and the display portion is pivoted to a front facing position relative to the arm portion. In the fourth configuration of the electronic device illustrated in FIGS. 28-35, the arm portion is pivoted to the lower position relative to the base portion and the display portion is pivoted to a rear facing position relative to the arm portion. The process or period in which the design transitions from one configuration to another forms no part of the claimed design.
